PHONE ATTACHMENT FOR HOLDING
WRITING MATERIALAnthony Zacharia, 5935 Colfax Ave.,
North Hollywood, Calif. 91601

Filed June 7, 1967, Ser. No. 7,396

Term of patent 14 years

(Cl. D26—14)

The broken lines are for illustrative purposes only.

I claim:

The ornamental design for a phone attachment for holding writing material, substantially as shown and described.
